UNITED STATES PATENT OFFICE

170,884

PORTABLE FOOD MIXER UNIT

Jack Morgan, Chicago, Ill., assignor to Dormeyer Corporation, Chicago, Ill., a corporation of Illinois

Application October 1, 1952, Serial No. 21,666

Term of patent 14 years

(Cl. D44—1)

To all whom it may concern:

Be it known that I, Jack Morgan, whose full and correct name is Jack Morgan, a citizen of the United States, residing in the city of Chicago, county of Cook, and State of Illinois, have invented a new, original, and ornamental Design for a Portable Food Mixer Unit, of which the following is a specification, reference being had to the accompanying drawings, forming a part thereof.

Fig. 1 is a side elevational view of a portable food mixer unit, showing my new design;

Fig. 2 is a top plan view thereof;

Fig. 3 is a front elevational view thereof;

Fig. 4 is a rear elevational view thereof; and

Fig. 5 is a perspective view thereof.

The side not shown is substantially like the side shown in Fig. 1.

The dominant feature of my design resides in the portable food mixer unit shown in full lines.

I claim:

The ornamental design for a portable food mixer unit, as shown and described.

JACK MORGAN.
